ELECTRIC LANTERN OR SIMILAR ARTICLE

Fredrick J. Kirkman, Freeport, Ill., assignor to Servel,
Inc., Evansville, Ind., a corporation of Delaware

Filed Jan. 7, 1960, Ser. No. 58,955

Term of patent 14 years

(Cl. D48—24)

Figure 1 is a perspective view of an electric lantern or similar article showing my new design;

Figure 2 is a top plan view thereof;

Figure 3 is a front elevational view thereof; and

Figure 4 is a rear elevational view thereof.

Figure 5 is a fragmentary cross-sectional view taken through line 5—5 of Fig. 4.

The side of the electric lantern not shown is substantially the same in appearance as the side shown.

I claim:

The ornamental design for an electric lantern or similar article, substantially as shown and described.
